UNITED STATES PATENT OFFICE

HENRY ZUCKWEILER, OF PEKIN, ILLINOIS.

TROLLING-HOOK.

SPECIFICATION forming part of Letters Patent No. 470,279, dated March 8, 1892.

Application filed April 22, 1891. Serial No. 389,983. (No model.)

To all whom it may concern:

Be it known that I, HENRY ZUCKWEILER, a citizen of the United States, residing at Pe-
kin, in the county of Tazewell and State of
Illinois, have invented certain new and useful
Improvements in Trolling-Hooks; and I do
declare the following to be a full, clear, and
exact description of the invention, such as
will enable others skilled in the art to which
it appertains to make and use the same, refer-
ence being had to the accompanying drawings,
and to the letters of reference marked there-
on, which form a part of this specification.

This invention relates to improvements in
trolling-hooks.

The object of the invention is to provide a
common spoon-hook with two swinging hooks
and a third stationary hook, (three being the
number generally used,) and the points of the
three hooks are designed to be brought to-
gether and inclosed in a suitable sheath hung
from the body of the hook, so that said points
are prevented from catching on obstacles un-
der the water, but which points may be set
free for work instantly by the pressure of a
fish (or other large animal life in the water)
against the said sheath in the attack of said
fish.

In the accompanying drawings, Figure 1
represents an elevation of the device, show-
ing a sheath depending from a lug or boss
attached to the body of the invention. Fig.
2 is also an elevation of the invention, show-
ing the points of the hooks inclosed in the
sheath. Fig. 3 is a detail view of the sheath
and hooks, showing the manner in which the
said hooks leave the said sheath. Fig. 4 is a
perspective view of the interior portion of the
invention, showing the manner in which the
hooks are held and operated. Fig. 5 is a per-
spective view of the sheath as detached from
the device.

A, Figs. 1 and 2, represents the body of the
invention, which consists of a short length of
tubing, to the upper end of which is soldered
a tapering tube B, and this tube B is sur-
mounted by a concave cap C, and to this cap
C is attached an eye c and wire d, ordinarily
used on devices of this class.

The internal constructions of the apparatus
may be understood from Fig. 4, in which an

upper and lower plate D and E, respectively,
are soldered within the tube or body A, and
the shanks F G H of three hooks I J K, re-
spectively, are passed up through holes for 55
the purpose in the said plates until the upper
ends of the said shanks are about one-quar-
ter of an inch above the upper plate D, after
which the shank G of hook J is soldered to
the said plate D, thus holding the hook rigid 60
therewith. The two remaining hooks I and
K are each provided with a collar L and M, re-
spectively, above the plate D, and which rest
thereon, and said hooks also carry a collar N
and O, which are placed underneath the said 65
plate D, and this holds the said hooks from
sliding up or down; also, the said hooks I
and K are provided, respectively, with col-
lars P and Q, which are soldered thereto, and
to each of these collars is soldered a wing or 70
arm a a. The ends of these wings or arms a
a press against a collar R, which is soldered
to the hook J, and which collar rests on the
plate E. The hooks I and K are intended to
swing freely, and in order that the said hooks 75
may always open after being released a spi-
ral spring S S is placed over the shanks of
each of said hooks, and the upper ends of said
springs are attached to the shank of the fixed
hook J, while the lower ends of said springs 80
are attached or placed behind the wings or
arms a a and may be soldered thereto, so that
when a strong pressure is given to the springs
when they are placed in the device the said
springs may always open and keep open the 85
said hooks I and K after the hooks have been
released, thus keeping the wings or arms a a
against the collar R when the hooks are not
inclosed in the sheath T.

The sheath T, mentioned above, is shown 90
in Figs. 1, 2, 3, and 5, and is of peculiar form,
and may be described as follows: A sheet of
metal T' is cut into the form shown, and
which tapers toward the top, and the extreme
upper portion is bent at right angles to the 95
body of the sheath to form an ear i, and by
this ear i the sheath is hung by a headed pin
k from a lug or projection l, soldered to the
body A. This construction allows the sheath
to move or swing in any direction with per- 100
fect ease and freedom.

The sheath proper is formed of a strip of

metal T, which is brazed or soldered to the portion T'. The lower end of this strip T drops down as far as the hook-barbs and is hollowed out, leaving a cheek g and g' on either side, and thus leaving or forming a depression f, in which the points or barbs of the several hooks are inclosed.

The operation of the device is as follows: When the two swinging hooks are turned or 10 swung toward the fixed hook, so that all three of the hooks or barbs are brought close together and all three of said barbs are directly in front of the sheath, the said sheath is pulled outward from the body, and thus 15 incloses the hooks in the cavity or depression f. Now, when thrown into the water and dragged, the device passes through and slips by the submerged obstructions without catching; but a fish in an attempt to swallow the 20 device will depress the sheath, and, drawing the said sheath away from the hooks, release the said hooks for work. The hooks on being released are thrown back to their normal positions, and the wings or arms on the 25 swinging hooks strike on the collar of the fixed hook, and the three hooks are thus held at equal distances from each other. Another action of the sheath may be understood from what follows and by referring to Fig. 3, and 30 in which figure it may be seen that from a simple light pressure on the point T' of the sheath the sheath proper (made up of the portion T and cheeks g and g') is turned to one side by reason of the binding of the hooks 35 in the sheath and by the binding of the pivot at the upper extremity, and that the cheek g' is carried downward away from the hooks, and the swinging hook I is released, which immediately springs back to its normal position, and at the same time the fixed hook J is 40 clear of the said cheek, and the remaining swinging hook K now having entire freedom swings around to its place and throws the

sheath aside and this leaves all parts in readiness for work.

45

I claim—

1. In a trolling-hook, the body A of tubing, the tapering portion B, mounted thereon, and the concave cap C, surmounting the said tapering portion, in combination with an upper plate D and a lower plate E, both inclosed within the said body A, a series of one or more hooks, the shanks of which pass up through both of said plates D and E, one of said hooks being fixed, the others movable, and a spring 55 placed on the shank of each of the swinging hooks, for the purposes herein set forth and described.

2. In a trolling-hook, the body A of tubing, the tapering portion B, mounted thereon, and 50 the concave cap C, surmounting the said tapering portion B, in combination with a sheath T, hung by pin k from a lug l on said body A, an upper plate D and a lower plate E, both inclosed within the said body A, a 55 series of one or more hooks, the shanks of which pass up through both of said plates, one of said hooks being fixed and the others movable, a spring placed on the shanks of each of the swinging hooks, and a wing or 70 arm on the said swinging hooks, for the purposes set forth and described.

3. In a trolling-hook, a sheath made of a curved plate tapering toward the top and having an ear or extension formed therewith 75 and a side projection on the said plate, said sheath being provided with a depending finger having an indenture formed therein, substantially of the shape shown and described, and for the purposes set forth.

8c

In testimony whereof I affix my signature in presence of two witnesses.

HENRY ZUCKWEILER.
